UNITED STATES PATENT OFFICE.

JOHN L. WEAVER, OF NEW ORLEANS, LOUISIANA

APPARATUS FOR WOOD DISTILLATION.

Application filed March 31, 1921. Serial No. 457,228.

To all whom it may concern:

Be it known that I, JOHN L. WEAVER, a citizen of the United States, residing at New Orleans, in the parish of Orleans and the State of Louisiana, have invented certain new and useful Improvements in Apparatus for Wood Distillation, of which the following is a specification.

This invention relates to a process and apparatus for the distillation of the volatile elements of wood, and more especially to the reduction of stumps of the species of pine found largely in the Gulf States. It has been found that the stumps remaining on the cut-over pine lands of many of the Southern States contain large amounts of rosin, turpentine, pine tar, pine oils, creosotes, flotation oils, and other ingredients, as for example wood alcohol, which can be extracted by the gradual application of heat, leaving a residue of pure charcoal.

These ingredients differ so in specific gravity that to properly secure them and to obtain the results aimed at, it is necessary that the stumps from which the material is to be obtained be subjected to a number of successive stages of heat, and that the temperature during the various stages be kept under perfect control. The main object of this invention is an apparatus by means of which this heat control may be obtained.

The invention also consists in the novel features of construction hereinafter described, pointed out in the claims, and shown in the accompanying drawings, in which:

Figure 1 is a side view of the complete apparatus, partly in elevation and partly in section.

Figure 2 is a section on the line 2--2 of Fig. 1.

Figure 3 is a section on the line 3--3 of Figure 4.

Figure 4 is a section on the line 4--4 of Fig. 2.

In carrying out the invention I construct a suitable firm masonry foundation, usually of cement, as indicated at 1. This is provided with a central recess into which extends a track 2 on which travels a truck 3. To one side of this central recess the foundation is again recessed to form a furnace or combustion chamber for producing heat, gases of combustion, in which chamber is located a grate 4. Mounted on this founda-

tion 1 is a retort 5, of brick, tile, stone or other suitable materials.

This retort is provided with double walls both being upwardly converging and circular, the inner wall 6 being about 4 inches thick and spaced about ten inches from the outer wall, which latter is about a foot in thickness. In the chamber between these two walls is a helical, screw-shaped partition 8, and as the space between the inner and outer walls of the retort communicates with the combustion chamber, this winding partition forms in said space a helical or screw-like flue.

A smoke stack 9 extends up one side of the retort and communicates by means of openings 10 with the flue above mentioned, each opening being immediately below one of the convolutions of the partition or flue wall 8. As shown these openings are three in number and products of combustion passing out through the uppermost of the openings 10 will circle around the retort three times. The two lower openings 10 are provided with hinged dampers 11 and operating handles 12.

The distillation chamber is formed by a steel tank 13 which fits snugly in the retort 5, forming a metal lining for it, and which extends slightly above it. It is provided with a removable cap or cover 13a. Its bottom covers the central recess in the foundation and is provided with hinged doors 14 normally held in a horizontal or closed position by a draw bar 15.

At one side of the retort is placed a condensing tank 16 having a condensing coil 18. A pipe 17 leads from the upper projecting portion of the distillation chamber 13 into the tank 16 and communicates with the condensing coil 18. The lower end of this coil drains into a small tank 19 which discharges through a drawoff cock 20 into a suitable receptacle 21.

It will be obvious from the drawings that the position of the dampers 11 will regulate the number of times the products of combustion will encircle the retort before escaping to the stack 9, thereby regulating the surface area of the wall 6 exposed to direct contact with said products of combustion, and by regulating this I retain control of the temperature in the distillation chamber 13.

The lowest temperature is of course ob-

2
tained by passing the said products of combustion out through the lowest of the openings 10. In operation the retort is charged by removing the cap 13^a, and then operated with the dampers open. At from eighty to one hundred degrees C. temperature the lightest and most volatile elements are passed off, as for example wood alcohol. At two hundred degrees C. turpentine is produced and at two hundred and fifty degrees C. various essential oils.

As more of the retort surface is brought into contact with the wall 6 by the closing of the lower damper 11 the temperature 15 rises, and at from two hundred and fifty to four hundred degrees C. heavy oils, rosin, creosote, and the like, are given off. With both dampers closed and a temperature running as high as six hundred degrees tar, 20 pitch and tar oils are extracted, and the residue, pure charcoal, is dumped by the dropping of the doors 14 into the truck 3, and thus removed. The cycle of operation 25 is then repeated. In practical tests seven burnings have been had from a retort during a month of twenty-eight working days.

From the above the practical advantages of the process and the apparatus for carrying it out will be obvious.

30 What I claim is:—

1. In wood distillation apparatus of the kind described, a distillation retort having walls spaced apart, a helical flue arranged between said walls, a combustion chamber communicating with the lower end of said flue, a stack communicating with the flue in different horizontal planes, and dampers regulating flow of products of combustion through said flue.

2. In wood distillation apparatus of the kind described, the combination with a distillation retort, of a helical flue, a stack communicating with the flue in different horizontal planes, and dampers controlling communication between the stack and the flue, the dampers being in different horizontal planes.

3. In wood distillation apparatus of the

kind described, a distillation retort having spaced walls, a metal receptacle fitting within the inner wall and projecting above the same, means for discharging charcoal through the bottom of said receptacle, a helical flue arranged between the walls and encircling said receptacle, a stack communicating with the flue in different horizontal planes, means for supplying heated combustion gases to the flue, means for controlling the circulation of the combustion gases in the flue and into the stack, and means for conveying from the receptacle the products of distillation.

4. In wood distillation apparatus of the kind described, a distillation retort having walls spaced apart, a helical flue arranged between said walls, a combustion chamber communicating with the lower end of the flue, a stack communicating with the flue in different horizontal planes, and dampers regulating flow of products of combustion through said flue.

5. In wood distillation apparatus of the kind described, the combination with a distillation retort, of a helical flue, a stack communicating with the flue in different horizontal planes, and dampers in vertical alignment for controlling communication between the stack and the flue.

6. In wood distillation apparatus of the kind described, comprising a distillation retort having upwardly converging, circular and spaced walls, a metal receptacle fitting within the inner wall and projecting above the same, means for discharging charcoal through the bottom of said receptacle, a helical flue arranged between the walls and encircling said receptacle, a stack communicating with the flue in different horizontal planes, means for supplying heated combustion gases to the flue, means for controlling the circulation of the heated combustion gases in the flue and into the stack, and means for conveying from the receptacle the products of distillation.

In testimony whereof I affix my signature.

JOHN L. WEAVER.
